UNITED STATES PATENT OFFICE.

JOHN STANLEY HUNTER, OF WAVERLEY, NEW SOUTH WALES, AUSTRALIA.

HYDRAULIC-ELEVATOR INSTALLATION.

Application filed October 22, 1923. Serial No. 670,157.

To all whom it may concern:

Be it known that I, JOHN STANLEY HUNTER, a subject of the King of Great Britain and Ireland, and resident of "Waldur Court," Paul Street, Waverley, in the State of New South Wales, Commonwealth of Australia, have invented certain new and useful Improvements in Hydraulic-Elevator Installations, for which I have filed application in Australia No. 12,556, on the 21st May, 1923, of which the following is a specification.

The purpose of this invention is to render impossible the operation or working of a hydraulic elevator if any one or more of the lift-well doors are open (unless the mechanism is tampered with) while not interfering in any way with the normal working of the elevator when all the doors are closed. The invention is applicable to elevator installations in which the lift-well doors are of vertically sliding type, horizontally sliding type, expanding type, and hinged type, the only alteration required in the respective cases being slight modifications in construction to enable the closure of any particular type of door to make the required mechanical contact which sets the mechanism forming the subject of this invention to release position so that the elevator may be operated.

A dangerous defect which has hitherto existed in hydraulic elevator installations is that it has been possible to remove the elevator car from any particular floor while leaving open the lift-well door at that floor, or while any lift-well door is open, and this has been the cause of many accidents. It is an object of this invention to prevent the occurrence of accidents from this cause.

My invention is applicable to installations in which the elevator car is operated by means of a hydraulic cylinder fitted with a ram, hydraulic engine, or any other hydraulically operated device by means of which the upward and downward movement of an elevator car is or may be effected.

My invention consists essentially in providing in a hydraulic elevator installation, a plurality of what may be termed hydraulic switches (which are actually valves) arranged in series and one of which is associated with each lift-well door above the lowest floor, and one (only) regulator valve arranged in the pressure supply pipe to the hydraulic machine, said cut-off valve being

set to the "on" or "open" position (that is permitting flow of water from the ordinary control valve when open to the hydraulic machine) by flow of water pressure through all the switches in series when these are set to the "on" or "open" position by closure of all the doors, and said cut-off valve being set to the "off" or exhaust position by a counter-balance weight, a spring or other known means, when on the opening of any lift-well door the switch associated therewith is automatically set to release the pressure operating the regulator valve.

My invention still further consists in other features as will be apparent from the following description in which reference is made to the accompanying drawings which depict apparatus and a method of installing same according to my invention.

In the drawings:

Fig. 1 is a diagrammatic sectional elevation of a conventional suspended elevator serving three floors of a building, and to which my invention is applied.

Fig. 2 is a longitudinal section of one of the hydraulic switches,

Fig. 3 a cross section thereof, and

Fig. 4 a longitudinal sectional elevation of the regulator valve and its control cylinder.

Referring to Fig. 1, the elevator car or cage 6 is suspended by rope 7 and is actuated by ram 8 working in hydraulic cylinder 9 in known manner.

The well-doors are indicated respectively by numerals 10, 11 and 12, and with same are associated respectively the hydraulic switches 13, 14 and 15, said switches being affixed in any suitable way to the well-framing and in such relative arrangement with the doors that their normally projecting plungers are contacted by the doors and forced inwardly when the latter are closed.

On the hydraulic service pipe 16 is a stop valve 17 and a control valve 18 of ordinary plunger type actuated by means of a hand rope 19 passing through the car 6, said hand rope being connected to a bell-crank lever 20 connected by link 21 to the plunger of the control valve 18. All of these parts are well known and need not be further described. From the valve 18 is a pressure pipe 22 leads to the regulator valve 23 whence a pressure pipe 24 leads to the hydraulic cylinder 9.

The regulator valve 23 is connected to an exhaust pipe 25 which is itself connected to

a main exhaust pipe 26 leading from the control valve 18.

The control cylinder for the regulator valve is indicated by numeral 27. A balance weight 28 is mounted on one arm of a bell crank lever 29 pivoted at 30, said lever tending to move the plunger of cylinder 27 inwardly as hereinafter explained.

From the service pipe 16 a branch service pipe 31 conveys pressure water to the top switch 15 which is connected by pipe 32 to switch 14. This switch is connected by pipe 33 to switch 13 which is connected by pipe 34 to the control cylinder 27.

Switches 13, 14 and 15 have exhaust pipes numbered respectively 35, 36 and 37 all connected to a common exhaust pipe 38 which leads into the main exhaust pipe 26.

Before describing the operation I will refer firstly to Figs. 2 and 3 illustrating one of the switches. The construction of these switches is identical, but for preference I have shown that indicated in Fig. 1 by numeral 15 and to which are connected the pressure supply pipe 31, outlet pipe 32 leading to switch 14, and exhaust pipe 37.

This switch 15 comprises a body 40 having an axial bore and fitted with end covers 41 and 42, water-tight joints being made by means of gaskets 43. Exhaust pipe 37 and outlet pipe 32 are connected to the body and communicate with the bore thereof, while pressure pipe 31 is connected to cover 41.

Within the bore of the body are four tubular distance pieces 44 holding in fixed spaced relation three annular U leathers 45. The two middle distance pieces are perforated while the two end ones have solid walls.

Slidable axially through the U leathers and distance pieces is a tubular plunger 46 of which the end opposed to cover 41 is closed, while in the other end is screwed a rod 47 which passes through a gland 48 on cover 42 and is terminally fitted with a head 49 on which is a buffer 50. Said plunger 46 has two series of radial apertures 51 and 52 so disposed that when the parts are in the position shown in Fig. 2, apertures 51 register with one of the perforated distance pieces 44 and apertures 52 with the other of said perforated distance pieces; and these perforated distance pieces are so arranged as to register respectively with the outlet pipe 32 and exhaust pipe 37.

Integral with the switch body 40 is a flange 53 provided with holes for the reception of bolts and screws 54 whereby the switch is attached to any convenient part of the lift-well framing or other convenient and suitable fixture and in such position that the buffer 50 is contacted by the lift-well door when closed and plunger 46 thereby moved axially to the left (Fig. 2) against the constant pressure exerted on the end thereof by water entering from pipe 31, and

which when the door is opened moves said plunger axially to the right to the position shown in Fig. 2.

When the parts are in this position it will be observed that water from pipe 31 cannot pass to either pipe 32 or pipe 37, but that pipe 32 is in communication with pipe 37 through apertures 51, bore of plunger 46 and apertures 52. The construction and arrangement is also such that the closure of the lift-well door and the consequent axial movement of plunger 46 brings apertures 52 into register with the left hand apertured distance piece 44, and apertures 51 past the left hand U leather 45. This establishes communication between pipes 31 and 32 through apertures 51, bore of plunger 46 and apertures 52.

I will now refer to Fig. 4 illustrating the regulator valve 23 and control cylinder 27. The regulator valve is similar, as regards the principles of construction, to the switches and I will therefore not describe it in minute detail but will describe its operation from which the constructional details will be apparent.

Pipe 22 leading from the control valve 18 is connected to the body 56 which is closed at one end by a solid head 57, and at the other end is fitted with a cover 58 through which passes the hollow plunger 59 closed at each end. The outer end of the plunger is connected to a cross head 60 apertured to accommodate the ball end 61 of the short arm of bell crank lever 29 which is pivoted at 30 on a stanchion 62 affixed to the base 63 on which are mounted the regulator valve and control cylinder 27. To the other end of crosshead 60 is connected a plunger 64 which enters the control cylinder 27 through a gland 65. Water pressure is admitted to the cylinder from pipe 34 which is the outlet pipe from switch 13 (see Fig. 1), and this water pressure forces the regulator valve plunger 59 to the position shown, i. e. the "on" or "open" position, and at the same time raises the balance weight 28.

When in this position, and the control valve 18 operated to admit water pressure to inlet pipe 22, this pressure passes through perforated distance piece 66 through apertures 67 in the hollow plunger 59 to the bore thereof, thence through apertures 68 in the plunger, through perforated distance piece 69 to pipe 24 and the hydraulic cylinder 9 for the working of the elevator upwardly. When the control valve 18 is set to exhaust, water flows in reverse direction from cylinder 9 and escapes through the exhaust pipe 26 from control valve 18 permitting the elevator to descend.

Should the pressure in control cylinder 27 be released, the balance weight 28 operates to move the plunger 59 in the reverse direction to the "off" or exhaust position wherein

apertures 68 register with perforated distance piece 66, and apertures 67 with perforated distance piece 70 and exhaust pipe 25. This effectively closes pipe 24 and locks water in the cylinder 9. When in this position operation of the control valve 18 to open position merely permits water to flow from pipe 22 to pipe 25 and thence to main exhaust pipe 26, while its operation to exhaust position has no effect whatever.

Pipe 32 in relation to switch 14 is equivalent to pipe 31 in regard to switch 15, and pipe 33 in relation to switch 13 is equivalent to pipes 31 and 32 in regard to the other switches, and it will therefore be obvious that if all the lift-well doors are closed and all the switches thereby set to the "on" or "open" position, a pressure circuit or path is established as follows:—from pipe 31 through switch 15, pipe 32, switch 14, pipe 33, switch 13 and pipe 34 to control cylinder 27. Pressure in the latter sets the regulator valve to the "on" or "open" position establishing communication between the cylinder 9 and the control valve 18 and permitting the ordinary working of the elevator.

If however one of the doors is open or partly open, the pressure from the inlet pipe of the switch associated with that door will set that switch to the "off" or exhaust position and establish communication between the outlet pipe of that switch and the exhaust thus relieving the pressure in the control cylinder 27. As an example of this I will assume that the door at floor 1 (Fig. 1) is partly open as shown. Pressure passes from pipe 31 through switch 15 to switch 14 and sets the latter to the "off" or exhaust position thus obstructing further flow. Thereupon the pressure in control cylinder 27 is cut off and communication is established between the control cylinder 27 and exhaust pipe 36 from switch 14. Balance weight 28 now asserts itself and moves plunger 64 inwardly into the control cylinder and at the same time moves plunger 59 to the "off" or exhaust, position. This movement is permitted by the fact that there is now no obstruction to the displacement of water in cylinder 27 by the plunger 64, the displaced water escaping through pipe 34, switch 13 (which is in the "on" position), pipe 33, through switch 14 to exhaust pipe 36.

A similar action occurs should any door be open, as will be readily understood. It is important to notice that any switch which is not (by the closure of the door) set to the "on" or "flow" position is automatically set to the "off" or exhaust position by the water pressure acting on its plunger.

The foregoing fully describes my invention as illustrated in the accompanying drawings but it is to be understood that I

do not confine my invention to what is actually described and illustrated as modifications falling within the scope of the appended claims may be made or even be rendered necessary to suit particular circumstances.

As the application of a switch to the lowest door of a lift-well may not always be required, the term "each lift-well door" or "all the lift-well doors," is, in this specification, intended to mean each door above the lowest or all the doors including the lowest.

What I claim and desire to secure by Letters Patent is:—

1. In an hydraulic elevator installation including a lift-well having a door at each floor, a car running in said well, and hydraulic car-operating mechanism controlled by a hand-operated valve in the service pipe, a fluid-pressure-actuated regulator valve inserted in the pressure supply pipe between said hand controlled valve and the operating mechanism, a control cylinder having a plunger connected with said regulator valve, an hydraulic switch comprising a cylindrically bored body having an inlet port connected to a fluid pressure supply pipe, an outlet port in communication with said control cylinder, an exhaust port, and a plunger slidable axially in said body and normally positioned to establish communication between said exhaust port and outlet port, and means actuated by said door when closed to move said plunger to establish communication between said inlet and outlet ports.

2. In an hydraulic elevator installation including a lift-well having a door at each served floor, a car running in said lift-well, car-operating means controlled by a hand-operated control valve in the service pipe, a regulator valve in the pressure pipe between said control valve and said car-operating mechanism, and a hydraulic control cylinder fitted with a plunger controlling said regulator valve, a series of hydraulic switches arranged and connected in series and associated individually with the respective doors of the lift-well, each of said switches comprising a cylindrically bored body fitted with a plunger slidable axially therein and subjected to fluid pressure tending to move same to one extreme position, said body having an inlet port an outlet port and an exhaust port, a fluid pressure supply pipe connected to the inlet port of the first in series of said switches, a pipe connection between the outlet of each switch (except the last in series) and the inlet of the next in series, and a pipe connection between the outlet of the last switch in series and the control cylinder, separate setting means connected individually to each switch plunger and actuated respectively by the lift-well doors when closed to move said plunger from

the extreme position aforesaid wherein communication is closed between said inlet and outlet ports but is established between said outlet and exhaust ports, to the other extreme position to establish communication between the inlet and outlet ports and permit flow of water to said control cylinder to move its plunger and set said regulator valve to open position, and means for returning said regulator valve to closed position when pressure in the control cylinder is released on the opening of a lift-well door and the constant fluid pressure in the switch moves the plunger thereof to the first extreme position.

3. In an hydraulic elevator installation in which the supply of fluid pressure to and the release of said pressure from the car operating mechanism is controlled by movement of one of the lift-well doors, a series of hydraulic switch associated individually with each lift-well door, each of said switches comprising a cylindrically bored body having an outlet port, an exhaust port and an inlet port to which is connected a fluid pressure supply pipe, annular leathers in the bore of the body one of said leathers being positioned between the inlet and outlet ports and another between the outlet and exhaust ports, a hollow plunger slideable through said leathers and moved to one extreme position by water pressure admitted through the inlet port, means actuated by the closure of the lift-well door to move said plunger to the other extreme position, said plunger having in its wall two separated sets of perforations so arranged that when the plunger is in the last mentioned

extreme position one set establishes communication between the inlet and outlet ports and when said plunger is the first mentioned extreme position communication is established between the outlet and exhaust ports, said switches being connected in series by means of a pipe connection from the outlet port of each (except the last in series) to the inlet port of the next in series, and a pipe connection from the last switch in series to hydraulically actuated means controlling the operation of a regulator valve interposed in the pressure supply pipe line to the car-operating mechanism.

4. In an hydraulic elevator installation a regulator valve of hollow perforated plunger type having inlet outlet and exhaust ports, a pipe connection between the outlet pipe and the car-operating mechanism, a fluid pressure supply pipe connected to the inlet pipe, a hydraulic cylinder having a plunger connected to the plunger of said regulator valve, hydraulic switches associated individually with each lift-well door and connected in series and to said hydraulic cylinder, said switches admitting water to said cylinder to actuate its ram and open said regulator valve when all the lift-well doors are closed but permitting said water to escape from said cylinder when any one of the lift-well doors is open, and means for returning the plungers of the regulator valve and hydraulic cylinder to normal position when the water pressure in said cylinder is released.

Signed at Sydney, N. S. W., this eighteenth day of September A. D. 1923.

JOHN STANLEY HUNTER.
